UNITED STATES PATENT OFFICE.

ALBERT L. GREEN, OF BUFORD, GEORGIA.

HAME AND TRACE CONNECTION.

SPECIFICATION forming part of Letters Patent No. 721,796, dated March 3, 1903.

Application filed September 16, 1901. Serial No. 75,562. (No model.)

To all whom it may concern:

Be it known that I, ALBERT L. GREEN, a citizen of the United States, residing at Buford, in the county of Gwinnett and State of Georgia, have invented a new and useful Hame and Trace Connection, of which the following is a specification.

This invention relates to hame and trace connections, and particularly to a clip and draft-eye construction, the purpose of which is to obviate and completely prevent wear on the collar by the clip through the medium of guard means provided in connection with the draft-eye, which will shield the collar, and thereby prolong the life of the collar without detracting in the least from the necessary durability of the connection or obstructing an easy assemblage of the trace-clip and draft-eye.

The invention consists in the construction and arrangement of the several parts, which will be more fully hereinafter described and claimed.

In the drawings, Figure 1 is a side elevation of a portion of a trace and clip and draft-eye embodying the features of the invention. Fig. 2 shows detail perspective views of the clip and draft-eye. Fig. 3 is a top plan view of the devices shown by Fig. 1, with a portion of the collar in dotted lines.

Similar characters of reference are employed to indicate corresponding parts in the several views.

The numeral 1 designates a trace of any preferred form and composed of connected plies and having a clip 2 secured to the front end thereof. The clip 2 is formed with a pair of flat shanks 3, which are inserted between the plies and secured by suitable rivets. From the front ends of the shanks the metal is continued in round form and looped or doubled to provide a clip-eye 4, which is given a slight torsional twist to dispose the shanks in apposition and also to project one portion of the eye 4 inwardly to a greater extent than the remaining portion, as clearly shown by Fig. 3, to produce a striking or bearing projection 5 and to establish an entrance-throat to the clip-eye. The eye 4 is arranged vertically and movably engages a draft-eye 6, suitably secured to the hame α and projecting rearwardly from the latter, as usual. The said

draft-eye comprises a body member 7 in the form of a plate, which is longitudinally curved and has a horizontally-disposed rib 8 at the center thereof on the outer side, the said rib widening toward the rear extremity thereof. By locating the rib 8 at the center of the body member guard-flanges 9 are produced above and below the said rib. The rear terminal 11 of the rib 8 is curved, so that the clip-eye 4 may easily ride or move thereover in an outward direction, and extending through the rear enlarged extremity of the said rib is a keyhole-slot 12 for convenience in assembling the clip 2 in relation to the draft-eye.

In the assemblage of the clip and draft-eye the one shank 3 is pushed downwardly through the slot 12, the clip being vertically positioned during such operation and so maintained until the eye 4 is reached, when the clip will be gradually turned to a horizontal position to bring the said eye 4 fully in the circular portion of the said keyhole-slot. After the clip has been placed in engagement with the eye 6, as set forth, the shanks 3 are then secured to the front extremity of the trace 1, and it will be impossible for the clip to become accidentally separated from the draft-eye, except in the event of breakage, which very rarely if ever occurs. It will also be seen that it is possible to separate the clip from the trace end and apply it to another trace in the event of breakage or injury to the trace to which it was first applied.

The draft-eye 6, when the hame carrying the same is applied to a collar, projects over a portion of the latter, as clearly shown by Fig. 3, and in the ordinary forms of clip and draft-eye the clip-eye is free to contact with and rub against or wear the leather of the collar and soon cause the latter to puncture or burst, so that the filling or stuffing of the collar-roll becomes exposed and the collar thereby seriously injured. The present construction obviates this wear on the collar by preventing the clip-eye 4 from contacting with any portion of the collar adjacent thereto. This restraint on the clip-eye is due to the guard-flanges 9, and it will be seen in Fig. 3 that the inwardly-projecting portion of the clip-eye 4 will strike against the lower guard-flange 9, and if the clip-eye swings in the slot 12, so as to bring the upper portion of the

said clip-eye inwardly, said latter portion will contact with the upper guard-flange 9, and hence the entire clip-eye is held out of possible engagement with the collar. The clip-
5 eye is free to move outwardly in relation to the draft-eye; but the longitudinal movement of the clip-eye in the slot 12 is very limited, and this restriction in movement will overcome any tendency of the clip-eye to draw
10 nearer to the collar or touch the latter. The guard features of the draft-eye are produced in a simple manner, and the body member or plate 7, as well as the rib 8, is made strong enough to withstand wear and resist fracture.
15 Various means may be employed for securing or attaching the draft-eye to the hame, and by the use of the improved device or connection a great saving in the wear and tear on a horse-collar will result. The inner side
20 of the draft-eye is smooth, and the portion of the collar contacting therewith or contiguous thereto will not become injured. It will also be seen that the trace-clip is free to swing inwardly and outwardly in a lateral direction
25 and also upwardly and downwardly, thus providing a universal joint or connection, which will relieve the coöperating parts of considerable strain.

Having thus described the invention, what
30 is claimed as new is—

1. A draft-eye comprising a body having

its inner side curved to lie on the outer side of a harness-collar and, having a longitudinal rib on its outer side, extending laterally therefrom, said rib having a vertical slot, and 35 said body having guard-flanges 9 above, below and extending in rear of the rib, in combination with a clip having an eye engaged with the slot in the rib, said clip, when under draft stress, bearing against the outer sides 40 of the flanges 9, and being by said flanges prevented from contacting with and wearing the collar, substantially as described.

2. A draft-eye comprising a body having a longitudinal rib on its outer side extending 45 laterally therefrom, said rib having a vertical slot and said body having guard-flanges 9, above and below, and extending in rear of the rib, in combination with a clip having an eye engaged with the slot in the rib, said clip, 50 when under draft stress, bearing against the outer sides of the flanges 9, and being by said flanges prevented from contacting with and wearing the collar, substantially as described.

In testimony that I claim the foregoing as my own I have hereto affixed my signature in the presence of two witnesses.

ALBERT L. GREEN.
